(57) **CLAIM**

The ornamental design for a removable rear ornamental
frame for a mobile phone case, as shown and described.

DESCRIPTION

FIG. 1 is a perspective view of a removable rear ornamental
frame for a mobile phone case showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view thereof taken along line 9-9
in FIG. 3;

FIG. 10 is another cross-sectional view thereof taken along
line 10-10 in FIG. 3; and,

FIG. 11 is a perspective view showing the removable rear
ornamental frame for a mobile phone case in a state of use.
The dash-dash broken lines depicting edges of the article in
FIGS. 1-10 represent unclaimed portions of the removable
rear ornamental frame for a mobile phone case which form
no part of the claimed design.

The dash-dash broken lines in FIG. 11 represent environment
subject matter which forms no part of the claimed
design.

The dot-dash broken lines represent unclaimed boundaries
to the claim.

1 Claim, 11 Drawing Sheets
